UNITED STATES PATENT OFFICE.

BENJAMIN W. DAVIS, OF CHICAGO, ILLINOIS.

SIGNAL SYSTEM FOR CONTROLLING STREET TRAFFIC.

1,328,269.

Specification of Letters Patent. Patented Jan. 20, 1920.

Application filed October 30, 1914. Serial No. 869,446.

To all whom it may concern:

Be it known that I, BENJAMIN W. DAVIS, a citizen of the United States, residing at Chicago, in the county of Cook and State of Illinois, have invented certain new and useful Improvements in Signal Systems for Controlling Street Traffic, of which the following is a specification.

This invention relates to signal systems and has for its principal object to provide a signal system for use in controlling traffic at street intersections.

It is now common practice to place at the intersections of busy streets in cities traffic policemen who control the passage of traffic by means of whistles or by signaling with their arms. This method of traffic control usually requires more than one traffic officer at each intersection, especially where the streets are very busy, and is open to the further objection that the signals are often confusing and not discernible. Whistles are often indistinct, or the sounds of whistles at neighboring street intersections are intermingled and confused, and their use necessitates that persons using the street be constantly on the alert to determine the number of blasts sounded.

The present invention aims to overcome these and many other disadvantages of present methods of traffic control by providing a system comprising distinctive signals easily discernible to the eye for indicating which street is open for traffic and which street or streets are closed to traffic at the intersection.

Another object is to provide a signal system actuated by an electric circuit, so arranged that the indication of the "clear" signal for one street may be given simultaneously with the block or danger signal for the other intersecting street or streets.

A further object is to provide a signal system which may be readily and conveniently operated by a signal traffic officer at each street intersection.

Still another object is to provide means for permitting operation of the signal system by the traffic officer in a wide range of positions adjacent the street intersection.

These and other objects will be more specifically set forth in the following specification taken in connection with the accompanying drawings, in which;

Figure 1 shows diagrammatically the circuit connections and general arrangement of

signal apparatus at the point of intersection of two streets;

Fig. 2 shows a side elevation of the signal apparatus for the intersection of two streets 60 showing a portion of one of the supporting posts broken away;

Fig. 3 is an enlarged detail of the right-hand supporting post shown in Fig. 2 with a portion of the wall thereof broken away to 65 disclose the arrangement of the cable within;

Fig. 4 shows a reduced plan view of the signal system shown in Fig. 2;

Fig. 5 shows a plan view of the signal system for use at the point of intersection of 70 three streets;

Fig. 6 is an enlarged perspective view of the signal member for the system shown in Fig. 5;

Fig. 7 is a diagrammatic view showing the 75 circuit connections and operating switch for the signal system shown in Figs. 5 and 6;

Fig. 8 shows an enlarged longitudinal section of the drum which supports the cable;

Fig. 9 shows an enlarged end view of the 80 drum shown in Fig. 8;

Fig. 10 shows a diagrammatic view of the arrangement and connections of signals for giving corresponding signals simultaneously at several different street crossings; 85

Fig. 11 shows a contact maker for use in automatically controlling a signal system;

Fig. 12 shows a modification of the device illustrated in Fig. 11;

Fig. 13 shows a plan view of a signal arrangement for the intersection of a street by a railway line; and 90

Fig. 14 is a plan view of a street intersection showing a modified arrangement of the signal members. 95

Like numerals and letters of reference refer to like parts and elements in the several figures of the drawings.

Referring to Fig. 2 the signal member 10 is shown as comprising four radiating signal elements or vanes 11, the opposite pairs of which lie in planes transversely of the streets 12 and 13, the boundaries of which are indicated in dotted lines in Fig. 1 and by full lines in Fig. 4. The signal member 10 may be supported by any suitable means and is preferably rigidly secured by means of brackets or clamps 14, or other suitable means, to two parallel wires or cables 15 and 16 which are secured at their ends by any 110 suitable means to the supporting posts 17 and 18 which are located in this construc-

tion at diagonally opposite street corners as shown in Fig. 4. When desired, the signal member may be mounted on a single post located at the center of the street crossing area or in any other suitable place as shown in Fig. 14, or, for instance, as shown at 24^a in Fig. 14, in which case the complete signal member for the two streets comprises two separate integral parts.

10 Each radiating signal element 11 has a portion of each opposite vertical face 19 formed of a sheet of stained glass or other suitable material of a distinctive color, so that when the interior of the signal element 15 is illuminated a light of a distinctive color will be projected from each signal element in opposite directions along the street which passes normally to the plane thereof. The vertical faces 19 of opposite signal elements 20 for the same street have their walls formed of plates of different colors so that one signal element may be actuated to indicate that the street is clear for traffic, while the other may be used to indicate that the street is 25 closed to traffic. For instance, the signal elements may have walls red and green in color, as indicated by the letters G', G² and R', R². The interior of each signal element is illuminated by electric lights preferably 30 two or more in number, as shown by dotted lines at 20. If preferred the faces 19 of the signal elements may be colorless and colored lights may be used within or with colored lights the faces may be omitted. The ends 35 19^a of the signal elements and the central partitions 19^b, shown in Fig. 6, are of some opaque material to prevent interference between the signals of different color and to prevent the projection thereof in improper 40 directions.

As shown in Fig. 1 the green signal element for one street has its lights connected in parallel with those on the red signal element for the other intersecting street. One 45 side of each of these parallel circuits is connected to a common feed wire 21 and the other side of each parallel circuit is connected to one of the wires 22 and 23. The wires 21, 22 and 23 are preferably carried 50 in a conduit 24 from the signal member 10 to a cut-out box 25 near the upper extremity of the supporting pole 18. From the cut-out box 25 the common feed wire 21 and the return circuit feed wire 26 extend downwardly in a circuit along the pole through 55 a switch box 27 and cut-out switch 28 to the supply circuit beneath the street level. From the cut-out box 25 the return circuit feed wire 26 and the two wires 22 and 23 are 60 formed in a flexible cable 29. At the end of the flexible cable 29 the wires 22, 23 and 26 are connected to a switch member 30 which may be actuated by the traffic officer to 65 control the operation of the signals. Within the switch member 30 the common return

conduit 26 is connected to a conducting member comprising the two spring blades 31 each formed with a hook or curve 32 adjacent its extremity. The conductors 22 and 23 are connected to the respective spring 70 contact blades 33 and 34, each of which is arranged parallel to one of the blades 31. The switch member comprises two push plugs 35 and 36 which are interconnected by means of the pivoted lever 37 and which terminate in the rounded heads 38 of conducting material of suitable form to pass between the spring blades 31-33 and 31-34 and to be engaged by the inwardly projecting portions 32 of said blades. It will thus 75 be seen that when one push plug 35 is pushed inwardly with respect to the switch casing a connection will be formed between the conductors 22 and 26, for instance, thus illuminating the signal elements R' and G². When 80 the other push plug is pushed inwardly to engage the contact blades 31-34, the first mentioned push plug will automatically pass out of engagement with its corresponding contact blades 31-33, thereby extinguishing 85 the signal elements R' and G², and the signal elements R² and G' will be illuminated. When the signal elements R' and G² are 90 illuminated persons on the street will know that the traffic is free to pass along the street 95 12 while passage is forbidden along the street 13, and when the signal elements just mentioned are darkened, R² and G' will be lighted and persons on the street will know that the traffic is then free to pass along the 100 street 13 at the intersection while its passage is forbidden along the street 12.

In order to permit the traffic officer to assume a wide range of positions adjacent the street intersection the flexible cable 29 is 105 passed over a pulley 39 suitably mounted on the supporting post 18 adjacent the upper extremity thereof. On the side of the pulley 39 opposite the switch member 30 the cable 29 then extends downwardly in 110 the form of a loop and has mounted thereon the traveling weight 40 carried by a pulley or drum 41 which coacts with the cable. When the traffic officer desires to assume a position outwardly from the pole 115 18, a downward pull on the outer end of the cable 29 will elevate the weight 40 and lengthen the cable at the outer side of the pulley 39. The drum or pulley 39 is preferably rotatably mounted on a shaft 39^a which has secured thereto a modified ratchet wheel 39^b having a notch adapted to coact with the pawl 39^c secured to the end of the drum. The drum is preferably recessed to receive the pawl and ratchet and a plate 41^c fits over 120 the end of the drum to close the recessed chamber. The cable is given one or more turns about the drum in order to form a firm frictional contact therewith and the cable may then be operated similarly to the 130

operation of a window curtain and maintained in any desired position. The weight 40 is preferably suspended within the supporting post 18 which is of a hollow construction, as shown in Figs. 2 and 3. A suitable block 42 is rigidly secured to the cable 29 at the outer side of the pulley 39 to limit the downward movement of the weight 40 and this block 42 is preferably so located as to bring the switch member 30 opposite the switch box 27 when said block 42 is in engagement with the pulley 39 so that when it is desired to discontinue the operation of the signal system, the cable 29 may be passed into the slot 43 in the lower face of the box 27 after the switch 28 has been thrown into open position. The door 27^a of the switch box 27 may then be locked and access to the signal system prevented while the traffic officer is off duty.

In Fig. 13 I have shown a street 12^a intersected by a railway line 13^a in which case the signal member 10^a comprises green and red signal elements actuated by an electric circuit comprising cables 24^c and 24^b which lead to contact makers 25^a, of a well known form, adapted to be actuated by the wheel flanges or other parts of passing cars. The circuit connections may be arranged to actuate the green and red signal elements in any desired manner, as will be apparent to those skilled in the art.

In Figs. 5, 6 and 7, I have illustrated the circuit connections and arrangement of elements of a signal system to be used at the intersection of three streets. In this case the signal member is preferably formed of three integral parts 45, 46 and 47, each comprising the red and green signal elements for one street. If desired, the signal member may be constructed according to this plan for use at the intersection of two streets, especially where they do not intersect at right angles. These separate members 45, 46 and 47 may be secured together by any suitable means and supported preferably between wires or cables 48 and 49 as in the previous case. The green and red signal elements are indicated in this case by the characters g' , g^2 , g^3 and r' , r^2 , r^3 and are connected as shown in Fig. 7, the common feed wire 21^a being connected to one terminal of the lamp circuit for each signal element. The other terminals of the lamps for the green signal elements g' , g^2 and g^3 are connected by means of the conductors 50, 51 and 52 to contact blades 53, 54 and 55, within the switch member 30^a. The lamp circuits of the red signal elements r' , r^2 and r^3 are connected by means of conductors 56, 57 and 58 to the respective contact blades 59, 60 and 61. The contact blades just mentioned are similar in form to those previously described and those for the red signal elements terminate in a line-

ment with the ends of the blades for the red signal elements and opposite each pair of blades so located is placed another contact blade 62 of the form shown in Fig. 7 each of which is connected to the common return conductor 26^a.

The connections between the contact blades 62 and the respective opposed contact blades 53, 54, 55 or 59, 60 and 61 are formed by means of push plugs 63 which are reciprocably mounted in the switch casing and which have heads 64 of suitable form to be tightly gripped between the projections of the contact blades 62 and the corresponding projecting extremities of the contact blades 53, 54, 55 and 59, 60 and 61. When the push buttons are in their normal position as shown in Fig. 7 they make contact between the blades 62 and each of the blades 59, 60 and 61, thus closing the circuits through the red signal elements r' , r^2 and r^3 , thereby indicating that each of the three intersecting streets are closed to the passage of traffic. When one of the push plugs 63 is pushed inwardly its head 64 makes contact between a blade 62 and one of the blades 53, 54 or 55, thereby closing the circuit for one of the green signal elements to indicate that the traffic is free to pass along the corresponding street. The plugs 63 are provided with insulating rings 64^a adjacent the heads 64 so that when a plug is pushed inwardly to light a green signal, the circuit for the corresponding red signal will be broken.

At the same time that one of the push plugs 63 is pushed inwardly to close the circuit for a green signal element, the other two push plugs should remain in the normal position shown in Fig. 7 so as to maintain a closed circuit for the red signal element of the two other intersecting streets, and to accomplish this purpose automatically, a system of levers are associated with the push plugs so that when one of them is pushed inwardly the other two will always be in the outer normal position. This mechanism comprises three levers 65, one of which is pivoted to each of the push plugs 63 and two other levers 66 which are pivoted on the switch casing. Each of the levers 66 is arranged to coact at each end thereof with the adjacent extremity of one of the levers 65, and each of the outer levers 65 has its outer extremity arranged to engage a notch 67 in the switch casing. At some point, preferably within the notches 67, sufficient backlash is left in the system of levers, as represented by the clearances 68, to permit one of the push plugs to be moved inwardly the proper amount to illuminate a green signal element, while the other two are in their outer normal position. If thereafter one of the other push plugs be pushed inwardly the last mentioned

push plug will, through the operation of the levers, be caused to move outwardly to its normal position so that when the green lights are burning for one street of the intersection, the red lights will be burning for the other two streets of the intersection, and this adjustment is made merely by pushing inwardly one of the push plugs.

In many instances, especially on very busy streets, it may be desirable, during certain hours of the day, to simultaneously operate the signals at different street crossings in such manner that the traffic will move in the same direction simultaneously in successive blocks of the same street, or on parallel streets. When the signals at different street intersections are actuated independently by individual traffic officers, it will be seen that the "clear" signals, indicating that the traffic is free to pass along a given street, will be given at different times by the officers at the different successive intersections along the same street, so that vehicles will be frequently interrupted and will be unable to pass continuously for any great space of time in one direction. It is, therefore, desirable to arrange the signal system for controlling the traffic in such manner that the "clear" signals, or the danger signals, will be given simultaneously at successive street intersections for the same street, and the provision of such a system constitutes a very important feature of the present invention.

For the purpose of illustrating the nature and operation of the above feature of the invention, I have shown in Fig. 10 two parallel streets, 70 and 71, intersecting two other right-angularly disposed parallel streets, 72 and 73, the boundaries of these streets being indicated by dotted lines. The signal members and the electric circuit for actuating the same are shown diagrammatically in their proper relation to the intersections of the above-named streets, the red and green signal elements of each signal member being designated by the letters R and G, respectively.

It will be seen that the green signal elements for the streets 70 and 71 at each intersection are connected in parallel with the red signal elements for the streets 72 and 73 at the corresponding intersections, while the green signal elements for the streets 72 and 73 are connected in parallel with the red signal elements for the streets 70 and 71. Each of these parallel circuits has one side thereof connected to a common feed wire designated by the numeral 74; the other terminals of the parallel circuits of the class first mentioned are each connected to a common conductor 75; and the other terminal of each parallel circuit of the class last mentioned is connected to a common conductor 76; the conductors 74, 75 and 76 correspond

to the conductors 21, 22 and 23, respectively, 65 shown in Fig. 1.

It will be understood that the current for the system is supplied through the common feed wire 74 and the return conductor 77, the conductor 77 and the two conductors 75 70 and 76 terminating in a switch member 30^b, similar to the switch 30, which may be actuated by the operator for simultaneously controlling the signals at different street intersections. 75

It will be evident from a study of the connections above described that when the green signal element is actuated at a given street intersection to indicate that the traffic is free to pass along one street of the intersection, the proper green signal elements at the other intersections will be simultaneously actuated to indicate that the traffic is free to pass at those intersections along the given street and, if so arranged, along 80 other parallel streets. By this method of traffic control drivers of vehicles may observe signals two or more blocks in advance of their position and may suitably regulate their speed so as to pass continuously for a 85 considerable distance without interruption. A further advantage of this method lies in the possibility of so actuating the signals as to permit the traffic to pass for relatively long periods of time along streets having the 90 greatest volume of traffic while allowing only relatively short periods for the traffic to pass on the intersecting streets having a 95 lesser volume of traffic.

Where the traffic on the streets is fairly 100 uniform in quantity, the signal system may be automatically actuated by a contact-maker of a well-known form which may be driven by a motor, or otherwise, to change the circuit connections at fixed intervals. 105 In Fig. 11 I have shown such a contact-maker, comprising a semi-circular plate 71, which is mounted on a shaft 79, to be continuously driven by a motor or other means; the common return conductor 77 may be 110 connected to this disk, and the two conductors 75 and 76 connected to brushes 80 and 81, one or the other of which is always in contact with the plate 71 so as to complete the circuit for one set of signals. 115 With a half revolution of the shaft 79 the circuit connections and setting of the signals will be changed, thus giving equal periods of time for the traffic to pass the intersection on each of the intersecting streets. 120

Where the traffic along some streets is greater in volume than that along other intersecting streets, it may be desirable to use a contact-maker of the form shown in Fig. 12, in which the brushes 80^a and 81^a are 125 adapted to contact with arcuate cam surfaces 82 and 83 of different lengths and at different times, so that the circuit connec-

tion for one set of signals will be maintained during a longer interval than the circuit connections for the other set of signals, thus permitting traffic to pass a greater 5 length of time on the streets having the greatest volume of traffic.

By means of the system of control just described, it may be possible to avoid the necessity of employing traffic officers at any 10 of the street intersections, unless it should be desirable to place an officer at the more busy street intersections to make sure that the signals are properly observed.

It will be apparent from the foregoing description that I have provided a novel and advantageous system for controlling street traffic. One of the great advantages of this system, in addition to those previously pointed out, is that the indication of the 15 signals can be observed by pedestrians, as well as by drivers of vehicles, some distance before the street crossing is reached, so that such driver or pedestrian may know before reaching the crossing whether or not 20 traffic is free to pass in the direction he wishes to go without the necessity of looking or listening for signals which cannot readily be distinguished. This is of a special advantage to automobilists who may observe 25 the change or time duration of a given set of signals before reaching a street intersection and thus be enabled to form a definite plan of action before reaching such intersection and thus avoid, in many instances, 30 the necessity of completely stopping their automobiles; for instance, by increasing speed the driver may cross the intersecting street before the signal changes, or by decreasing speed, avoid reaching the crossing 35 until the same is opened to him.

While I have described a specific embodiment of my invention for the purpose of illustrating the nature and advantages thereof, it will be understood that it may be 40 modified in form and arrangement without departing from the scope of the invention as defined by the appended claims.

What I claim is:—

1. In a signal system for controlling street 50 traffic, a signal member comprising distinctive signal elements, an electric circuit for illuminating said signal elements, said circuit comprising an extensible cable, and a switch member carried by said cable.

2. In a signal system for controlling street 55 traffic, signal members located adjacent each of a plurality of street intersections, each signal member comprising a "danger" signal element and a "clear" signal element for each street of the adjacent intersection, and 60 means to actuate the "clear" signal elements for parallel streets at different intersections, and the "danger" signal elements for the streets which intersect said parallel streets at those intersections simultaneously, 65 said means comprising an automatic contact-maker.

3. In a signal system for controlling street 70 traffic, a signal member comprising distinctive signal elements, a supporting structure for said signal member, an electric circuit for actuating said signal member, a switch for the electric circuit, said circuit including a flexible cable by which said switch is carried, and means for varying the 75 effective length of said flexible cable.

4. In a signal system of the class described, a signal member comprising a plurality of signal elements, a supporting structure comprising a hollow post, an electric 80 circuit for actuating said signal elements, said circuit comprising a flexible cable having a part thereof disposed within said hollow post, means carried by said post for regulating the length of cable on the outer 85 side of said post, and means carried by said cable for controlling said electric circuit.

5. In a signal system for controlling traffic at intersecting ways, in combination, signal members positioned at the intersection 90 of said ways, each of said members having a "danger" indicating element and a "clear" indicating element for each of the intersecting ways, means for actuating said member, said means being arranged to project a "clear" signal in both directions along one of said ways and a "danger" signal in both directions along the intersecting ways, and means for controlling said actuating means from a plurality of points, 95 said latter means including an extensible cable.

In testimony whereof, I have subscribed my name.

BENJAMIN W. DAVIS.
